UNITED STATES PATENT OFFICE.

CHARLES THERON HEADLEY, OF BRUNSWICK, GEORGIA.

ROTARY CUTTER.

SPECIFICATION forming part of Letters Patent No. 746,959, dated December 15, 1903.

Application filed August 27, 1903. Serial No. 170,947. (No model.)

To all whom it may concern:

Be it known that I, CHARLES THERON HEADLEY, a citizen of the United States, and a resident of Brunswick, in the county of Glynn and State of Georgia, have made certain new and useful Improvements in Rotary Cutters, of which the following is a specification.

My invention is an improvement in that class of woodworking-machines which are provided with rotary heads having cutters adapted to form grooves or slots for various purposes. My invention is more particularly an improved attachment for such rotary heads, the same comprising a bracket or foundation-piece of peculiar construction and a series of grooving-cutters, which are applied and secured to the bracket in an improved manner.

The details of construction, combination, and operation of parts are as hereinafter described, reference being had to accompanying drawings, in which—

Figure 1 is an end view of a rotary cutter-head with my improved attachment applied thereto, the shaft or arbor being shown in section. Fig. 2 is a side and front view of the parts shown in Fig. 1. Fig. 3 is a top or plan view of the same parts. Fig. 4 is a perspective view of the bracket or foundation-piece detached. Figs. 5 and 6 are perspective views of the cutters. Fig. 7 is a side view representing a modification. Fig. 8 is a side and front view of the parts shown in Fig. 7.

I will first describe my invention as illustrated in Figs. 1 to 6. The square cutter-head A is provided with T-grooves and applied to the shaft or arbor B in the usual way. My improved bracket or foundation-piece C, to which the cutters D and E are attached, (see Figs. 5, 6) is provided with lateral base-flanges c, (see Fig. 4,) having slots c', through which bolts c² are inserted for securing the bracket to the head A. The centrally and outwardly projecting portion c³ of the bracket has its outer side or edge curved upon the arc of a circle corresponding to a radius of the arbor B, and its front end or nose c⁴ is extended beyond the side flanges c and curved on the under side, which is provided with a series of ratchet-notches c⁵. In other words,

the under side of the nose or point c⁴ is curved on its under side corresponding to the arc of a circle, and the grooves or notches c⁵ are formed transversely at the rear and middle portion of the arc, the outer portion of the arc being left smooth or plain. The cutter D has a corresponding curve and is provided exteriorly on its rear and middle portion with a series of transverse ratchet-teeth c⁶, corresponding in form and angle with the grooves or notches c⁵. Thus when the cutter D is applied, as shown in Fig. 1, its rearwardly-projecting teeth enter and fit neatly in the forwardly-projecting or tangential grooves c⁵, while its plain portion rests against the corresponding outer portion of the nose c⁴. The cutter D is secured in place by means of a lag-screw G and a block F, (see Fig. 5)—that is to say, the inner face or side of the block is grooved corresponding to the outer or lower side of the cutter D, and the lag-screw G passes through the same and through a longitudinal slot formed in the cutter D. It will be seen that by this construction, combination, and arrangement of parts I provide a very firm support for the cutter D, also one which effectively resists back thrust, while the cutter is adapted for convenient adjustment, so that it may be projected beyond the point c⁴ of the bracket, as required for cutting grooves of different depths. It will be understood that the radially-projecting portion of the bracket is made slightly less in thickness or width than the width of the cutter D, so that good clearance is provided in actual work.

It will be observed that in addition to the function above-stated the coincident or matching ratchet-teeth and grooves of the cutter D and the bracket C serve, further, to prevent any lateral movement of the cutter, which is an advantage of importance in this class of machines. It will be noted that the lateral flanges c of the bracket are separated or grooved at the front end, so that the cutter D may extend back as far as permitted by the plane surface of the cutter-head A, also that the block F seats upon such surface of the cutter-head and is therefore held very rigidly in the desired position.

The cutter D is intended chiefly for cutting across the grain, and I employ in conjunction

with it two spur side cutters E, which are constructed and applied as follows:

As shown in Fig. 4, the radially-extended portion c^3 of the bracket C is provided with 5 two opposite dovetailed grooves c^7 , which are arranged tangentially or at a forward inclination of about forty-five degrees. A longitudinal slot c^8 is provided in the center of the grooves. The cutters E (see Figs. 1, 2, and 6) 10 are provided with beveled side edges and adapted to fit neatly in the said grooves and for lengthwise adjustment therein, the cutters being secured by means of a screw c^9 arranged transversely and passing through the slot c^8 . 15 The outer projecting ends of the cutters E are serrated, so that a toothed or saw-like edge is produced. The cutters E project laterally slightly more than the width or lateral thickness of the cutter D, so that in operation they 20 cut the sides of the groove, while the cutter D clears out the fibers thus separated at their ends. It will be further noted, by reference to Fig. 2, that the cutters E incline slightly inward from their outer ends, so that good 25 clearance is always obtained, or, in other words, the cutters do not bind or stick in the groove formed by them.

The cutters D and E are adapted for forming relatively deep grooves; but for still 30 deeper ones I may employ the construction and arrangement of parts indicated in Figs. 7 and 8, where the radial portion of the cutter-head C' is provided with a less extended or blunter point and the cutter D' is curved 35 corresponding to the arc of a circle of less radius than the cutter D, so that it does not extend into a notch, as indicated in Figs. 1 and 4. The brackets C' are provided on one side only with a lateral flange c^{10} , which is 40 right angular in form, being so constructed that it is applied to the adjacent plane surfaces of the cutter-head A. Bolts c^{11} are applied to both angles of the flange c^{10} , as shown. As indicated in Fig. 8, the cutter-head proper, 45 C', is located adjacent to one end of the cutter-head A. By means of such angular flange c^{10} I provide for the firmest possible attachment of the bracket.

It will be seen that my improved grooving 50 attachment is adapted for application to rotary cutter-heads already in use or of the ordinary construction and that it may be attached or detached with the same facility as an ordinary cutter.

55 What I claim is—

1. The combination, with a bracket adapted for attachment to a rotary cutter-head, and having a radial portion provided with a forwardly-extended nose, or point, whose under 60 side is constructed with transverse ratchet-grooves, of a cutter curved correspondingly and having transverse ratchet-teeth adapted to fit in said grooves, and means for securing said cutter in place, substantially as described.

2. The combination, with the bracket adapted for attachment to a rotary cutter-head and having a radially-extended portion whose forwardly-projecting nose, or point, is curved on its under side and provided with 70 transverse ratchet-grooves, of a clearing-cutter which is curved upon a corresponding arc and provided with transverse ratchet-teeth adapted to fit in said grooves, and a block and lag-screw applied for securing the cutter, 75 substantially as described.

3. The combination, with a rotary cutter-head having a plane surface, of the improved grooving attachment comprising a bracket having base-flanges, a narrow radial portion 80 having its nose, or point, curved on the under-side and provided with transverse ratchet-grooves, a clearing-cutter having a corresponding curvature, and transverse ratchet-teeth projecting rearward and adapted to fit 85 in the said grooves, a block fitting the under side of the cutter and abutting the adjacent side of the cutter-head, and a screw-bolt securing said cutter and block in the manner described.

4. The combination, with the cutter-head and the bracket secured thereto and having a thin radial portion whose projecting point is curved and provided with transverse ratchet-grooves and base-flanges which are 95 separated adjacent to such grooves, of a clearing-cutter curved corresponding to the seat provided on the bracket and having rearwardly-projecting ratchet-teeth, that engage the aforesaid grooves, and also a longitudinal slot, and a block shaped on its inner face corresponding to the cutter and its lower end resting upon the cutter-head, and a screw-bolt securing the cutter-block in the manner described.

5. The combination, with the bracket adapted for attachment to a rotary cutter-head and having a thin radially-projecting portion provided with opposite, tangential, dovetailed grooves and a slot extending from one to the other, of serrated cutters adapted to fit and slide in said grooves, and a screw passing through the slot and securing the cutters in the manner described.

6. The combination, with the bracket having a thin radially-extended portion provided with a forwardly-extending nose, or point, of a clearing-cutter applied to the curved under side of said point, and serrated cutters arranged in slots formed in the sides of the projecting portion and projecting laterally to a greater distance than the width of the clearing-cutter, substantially as described.

7. The combination, with a rotary cutter-head having adjacent plane surfaces, of a bracket having seats for grooving-cutters and a base-flange projecting from one side, the said flange being right angular in form and thus adapted to embrace an angle of the cutter-head and means for securing the bracket 125 130

to the cutter - head, substantially as described.

8. The improved bracket adapted for attachment to a rotary cutter-head, the same consisting of a horizontal base portion and a 5 radially-projecting thin portion having a projecting nose or point provided with a seat for

a clearing-cutter and having in rear thereof inclined seats for side cutters, substantially as described.
